UNITED STATES PATENT OFFICE

156,320

IMPACT WRENCH UNIT

Aileen Bushnell, Aurora, Ill., assignor to Independent Pneumatic Tool Company, Aurora, Ill., a corporation of Delaware

Application September 2, 1948, Serial No. 148,442

Term of patent 14 years

(Cl. D54—14)

To all whom it may concern:

Be it known that I, Aileen Bushnell, a citizen of the United States, residing at Aurora in the county of Kane, State of Illinois, have invented a new, original, and ornamental Design for an Impact Wrench Unit, of which the following is a specification, reference being had to the accompanying drawing, forming a part thereof, wherein:

Figure 1 is a side elevational view of the impact wrench unit, showing my new design.

Figure 2 is a view from one end of the impact wrench unit shown in Fig. 1.

Figure 3 is a view from the other end of the impact wrench unit shown in Fig. 1.

I claim:

The ornamental design for an impact wrench unit, substantially as shown.

AILEEN BUSHNELL.
